CIRCUIT ARRANGEMENT FOR AUTOMATIC
TELEPHONE INSTALLATIONS

Egon Zirzow, Berlin, and Herbert Töpfer, Berlin-Siemensstadt, Germany, assignors to "Fides Gesellschaft für die Verwaltung und Verwertung von gewerblichen Schutzrechten mit beschränkter Haftung," Berlin, Germany, a corporation of Germany

Application August 25, 1939, Serial No. 291,810
In Germany August 30, 1938

4 Claims. (Cl. 179—16)

The invention relates to means for insuring the release of an interexchange connection at any time during the establishment of such connection when the calling party desires such release. When an interexchange trunk line conductively blocked by repeating coils is used for such connection it is sometimes difficult to prevent interference between signals transmitted in one direction for release and signals transmitted in the other direction for metering and the like. In order to insure release when a calling subscriber hangs up even though this occurs before the called subscriber has answered, after he has answered or at the same time, we have provided an arrangement for sending a single inductively transmitted impulse when release is desired before the called party has answered and by means of a series of short successive inductive impulses after the called party has answered.

In the present system we have shown an interexchange trunk line VL terminating in an outgoing repeater Ue1 (Fig. 1) in one exchange and an incoming repeater Ue2 (Fig. 3) in the called or terminating exchange. Each repeater is connected to the trunk line VL by means of a repeating coil.

When the outgoing end of repeater Ue1 is seized to extend a connection over the trunk line or junction VL through repeater Ue2 (Fig. 3) the equipment in Ue1 is operated to send over the trunk line positive and negative induced impulses for operating the usual switches to extend the connection. The signal returned when the called subscriber responds by lifting his receiver is sent back over the trunk line VL by means of alternating current. The release before the response of the called party is accomplished by a single induced impulse, while after the called party has answered and should the calling party wish to release then a series of short successive induced pulses are transmitted.

The accompanying figures show two embodiments of the invention. Figures 1 and 3 show an embodiment in which all the switch operations are transmitted from the outgoing to the incoming end of the junction by induced impulses. In particular the release signal, transmitted when the calling subscriber hangs up his receiver after the signal for the conversation to begin, which occurs on the reply of the called subscriber, is sent by means of an odd number of alternations of positive and negative inductive impulses separated by short pauses.

On the other hand Figure 2 shows an embodiment in which the release impulse, transmitted

after the called subscriber has replied is accomplished not by means of inductive impulses transmitted when the calling subscriber hangs up his receiver but by alternating current impulses.

5 In the reverse direction signals are transmitted in both embodiments by alternating current impulses. Instead of the alternating current impulses it is understood that signals in the reverse direction can also be transmitted as induced impulses without essentially altering the nature of the invention in any way.

In order to ensure that the release impulses get through, their frequency is made higher than the frequency of the impulses proceeding in the 15 reverse direction. Moreover the duration of the release impulse is at least longer than 1 period of the impulses in the reverse direction.

The embodiment shows an arrangement with a trunk line arranged for uni-directional traffic. 20 The invention it is understood, can also be used for traffic in two directions.

The method of working of the arrangement in Figs. 1 and 2 is as follows:

Seizure

25 On the seizing of the repeater Ue1 (Fig. 1) on the outgoing end of the junction VL by means of a group selector (not shown) the relay C1 is energised over the c-conductor: earth, test relay, test wiper of the series group selector, conductor c, contacts 11x1, 12h1, 13b1, 15c1, winding II of relay C1, battery, earth. Relay C1, by opening its contact 15c1 and closing its contact 14c1, connects its high resistance winding I in series 30 with winding II in the seizing circuit and holds over this contact independently of relays X1, H1 and B1. Relay C1 closes the following circuit for relay A1 at contacts 26c1: earth, contact 21i1, winding II of relay A1, contact 19x1, winding III of relay C1, contact 26c1, battery, earth. Moreover, before relay A1 is energized, relay C1 closes the following circuit over the winding I of the 35 transformer Tr: earth, contacts 9b1, 30x1, 32c1, winding I of transformer Tr, battery, earth. 40 Thus in the winding II of transformer Tr, an impulse is induced which however is without effect since the contact 35a1 is not yet closed. Relay A1 closes the following circuit for relay B1: earth, contacts 21i1, 17a1, winding I of relay B1, winding I of relay V1, contact 26c1, battery, earth. Relay B1 operates in series with relay V1. Relay B1 at contact 9b1 interrupts the circuit of the winding I of transformer Tr. Thus in the winding II of the transformer Tr an inductive impulse 45 is produced whose direction is indicated as nega-

tive. This impulse, which extends over contacts 35a1, 37e1, 38v1 and after the operation of the relay V1 directly over contact 39v1 and the primary winding of the transformer blocking the line, is transmitted over the junction VL to the incoming repeater Ue2 (Fig. 3). The polarisation of the accepting relay P2 (Fig. 3) shunting the line, is arranged so that this impulse is without effect on the armature of the relay. The impulse furthermore serves to effect a complete demagnetisation of the relay P2 so far as any residual field is concerned. Relay B1 (Fig. 1) closes the following circuit for relay XI: earth, contact 21i1, winding I of relay XI, contacts 18b1, 26c1, battery, earth. Relay XI operates and closes a further circuit over the winding I of transformer Tr: earth, contacts 10b1, 31x1, 32c1, winding I of transformer Tr, battery, earth. By the closing of this circuit an inductive impulse in the positive direction is produced in the winding II of the transformer Tr which extends over the junction VL to the polarised accepting relay P2 in the incoming repeater Ue2. Thus as is shown later the repeater Ue2 is seized. In the outgoing repeater Ue1 after the energising of relay XI at contact 19x1 the circuit for the winding II of relay A1 is interrupted and this relay restores. By the release of relay A1 at contact 17a1 the circuits for relays B1 and VI are opened. Relays B1 and VI restore and the latter in view of the short circuit over contact 29y1 for its winding II has a delayed release. By the release of relay B1 at contact 10b1 the circuit over the winding I of transformer Tr is interrupted. By the opening of this circuit, in the winding II of the transformer Tr, a negative inductive impulse is produced which, since the contact 39v1 is still closed, extends over the junction VL to the polarised accepting relay P2 of the repeater Ue2. The armature of the relay P2 is thus set back to its initial position. In the outgoing repeater Ue1 after the release of relay B1 the circuit for the winding I of relay XI at contact 18b1 is interrupted. The relay holds in the following circuit however: earth, contacts 46x1, 50h1 and 48a1, winding II of relay XI, battery, earth.

In the incoming repeater Ue2 as already mentioned by means of the positive seizing impulse, which extends over the winding I of relay P2 shunted across the line, the seizing operation is initiated. It should first be stated that the relay E2 is energised in the normal condition of the installation over its high resistance winding I and the c-conductor to the following group selector. Thus over the closed contacts 61e2 and 64e2 the circuit for the accepting relay P2 is completed. The relay P2 after its operation closes the following circuit for relay A2: earth, contacts 90p2, 78f2, winding of relay A2, battery, earth. Relay A2 operates and closes the following circuit for the seizing relay C2: earth, winding of relay C2, contacts 103a2, 101v2, resistance Wi2, battery, earth. Relay C2 operates and holds independently of relays A2 and V2 in the following circuit: earth, winding of relay C2, contacts 99f2, 107c2, resistance Wi2, battery, earth. Further, relay C2 by direct earthing of the c-conductor over contact 76c2 seizes the connected group selector in known manner. Since the winding I of relay E2 thus is short-circuited, relay E2 is maintained energised over its winding II in the following circuit: earth, contacts 81s2, 86c2, winding I of relay V2, contacts 89m2, 106f2, winding II of relay E2, battery, earth. In this circuit the slow relay V2 also

operates. The seizing relay C2 which is now short-circuited over contacts 102v2, 103a2 is however not restored, since by means of the negative inductive impulse arriving after the short 5 interval relay P2 and hence also relay A2 are restored before relay C2 releases. The relay V2 is then short-circuited over contact 81a2 and restores. After the release of relay A2 the circuit for relay U2 is completed: earth, contacts 81s2, 10 86c2, 87a2, winding II of relay U2, contacts 88a2, 83m2, resistance Wi3, battery, earth. Over its contact 84u2 relay U2 prepares a holding circuit including the two windings I and II in series which circuit is independent of relay A2. Further by closing its contact 94u2 relay U2 prepares a circuit for its winding III.

Transmission of operating impulses

By means of the numerical selection in the group selector (not shown) impulses received from the repeater Ue1, earth is connected intermittently to the a-conductor (Fig. 1) and thus the winding I of the relay A1 of the repeater Ue1 is intermittently energised: earth in the group selector, conductor a, contacts 1h1, 56x1, winding I of relay A1 contacts 3y1, 5e1, battery, earth. Relay A1 operates and over contact 17a1 energises relays B1 and VI. Relay VI holds as a slow relay during the impulse train. Relay B1 on each operation closes over contact 10b1 a circuit over the winding I of the transformer Tr and thus produces a positive inductive impulse over the junction VL. When the relay A1 restores the circuit for relay B1 is interrupted and relay B1 restores interrupting the circuit over winding I of the transformer Tr. Thus a negative inductive impulse is transmitted over the junction. In this manner in the numerical selection alternative positive and negative inductive impulses are transmitted over the junction.

In the incoming repeater Ue2 during the numerical selection the armature of the relay P2 is operated and then shortly afterwards restored by means of a pair of inductive impulses, one in the positive and one in the negative directions; thus the contact 90p2 is momentarily closed and opened. By the closing of contact 90p2 relay A2 is energised. Relay A2 interrupts the short circuit for the slow relay V2 at contact 87a2 so that this also operates. Relay V2 holds during the impulse train. Relay V2 is maintained energised in the following circuit when contact 88a2 is opened during the impulse transmission: earth, contacts 81s2, 86c2, winding I of relay V2, contact 89m2, windings II and I of relay U2, contacts 84u2, 83m2, resistance Wi3, battery, earth. The impulses are transmitted by means of relay A2 in the following circuit to the connected group selector: earth, contacts 70u2, 68a2, 69c2, conductor a, impulse accepting relay of the group selector which follows, battery, earth. During the impulse train control potential is connected to the b-conductor in the following circuit: earth, battery, contacts 75m2, 74s2, 72v2, conductor b. The seizing relay C2 short-circuited over contact 102v2 and the intermittently closed contact 103a2 during the impulse train is not restored during a single impulse train. Moreover during an impulse train the a-conductor is interrupted by means of contact 65v2 in the direction opposite to the blocking transformer so that any undesired charging up of the talking condenser by the impulse transmission may be avoided.

Release control

The case is now considered in which the calling subscriber hangs up during the impulse selection before the called subscriber has replied and thus initiates the release. In the group selector which has seized the outgoing repeater U_{e1} the c -conductor is thus interrupted. The relay $C1$ of the repeater U_{e1} is restored. Thus relay $A1$ is energised again in the following circuit: earth, contact $21i1$, winding II of relay $A1$, contacts $20x1$, $23y1$, winding II of relay $H1$, contacts $25a1$, $27c1$, battery, earth. Before relay $H1$ which is slow to operate has energised in this circuit its winding II is again short-circuited over contact $24a1$. By the opening of contact $25a1$ the short circuit for winding I of relay $E1$ is interrupted. Relay $E1$ slowly operates in series with the winding II of relay $A1$. On the operation of relay $A1$ the following circuit is completed over the winding I of transformer Tr : earth, contacts $48a1$, $38c1$, winding I of transformer Tr , battery, earth. Thus a positive impulse is induced in the winding II of the transformer Tr which as long as the relay $E1$ has not yet operated is transmitted over this transformer winding and over the contacts $35a1$, $37e1$, $38v1$ to the blocking transformer and from this over the junction VL to the incoming repeater U_{e2} . The negative inductive impulse which follows is suppressed by the operation of relay $E1$ which interrupts the repeater circuit at contact $37e1$. As soon as relay $E1$ has operated the following circuit is completed for relay $B1$: earth, contacts $43x1$, $43h1$, $43v1$, $42e1$, $45c1$, winding II of relay $B1$, battery, earth. Relay $B1$ by means of its contact $55b1$ short-circuits the holding circuit for the winding II of relay $X1$. Relay $X1$ thus restores and interrupts the circuit for the winding II of relay $B1$ which restores. By the release of relay $X1$ the circuit for relays $A1$ and $E1$ is also interrupted at contact $20x1$ and both relays restore. Thus all the relays for the repeater U_{e1} are in their normal positions.

In the repeater U_{e2} by means of the positive release inductive impulse over winding I the accepting relay $P2$ is energized. Contact $90p2$ closes a longer energising circuit for relay $A2$. Relay $A2$ interrupts at contacts $87a2$ the short-circuit for relay $V2$ and relay $V2$ also operates. The seizing relay $C2$ is now short-circuited over contacts $102v2$ and $103a2$ so that it restores. By the release of the relay $C2$ the seizing of the c -conductor as far as the group selector connected with contact $76c2$ is discontinued and its release initiated. After the release of relay $C2$ by means of the opening of contact $86c2$ the circuit for relays $V2$ and $E2$ is interrupted and also the circuit for relay $U2$. The relays restore. Thus the following circuit is completed for relay $F2$: earth, winding II of relay $F2$, contacts $97c2$, $98e2$, battery, earth. Relay $F2$ operates and closes the following circuit for winding II of relay $P2$: earth, contacts $93u2$, $92f2$, winding II of relay $P2$, battery, earth. Over this winding which is a reverse winding to the winding I the armature of the relay $P2$ is again set back to normal so that relay $A2$ restores. As soon as the group selector seized by repeater U_{e2} has been released the high resistance winding I of relay $E2$ is operated again in known manner over the principal contact of this selector and on the one hand at contact $93e2$ interrupts the circuit for relay $F2$ and on the other hand again disconnects the blocking alternating current connected

during the release of relay $E2$ over contacts $62e2$ and $63e2$ back over the junction.

In the repeater U_{e1} by means of the blocking alternating current transmitted revertively over the junction VL the relay $J1$ is energised in the following circuit: repeater windings, contacts $38v1$, $36e1$, winding of relay $J1$, repeater winding. The relay $J1$ closes the following circuit for the relay $H1$: earth, contact $22i1$, winding III of relay $H1$, earth. Relay $H1$ by opening contact $12h1$ interrupts the incoming c -conductor and thus prevents the premature seizing of the repeater U_{e1} . As soon as the release has been accomplished at the incoming end of the line the relays $J1$ and $H1$ restore and the guarding is discontinued.

Response of called subscriber

The case is now considered in which the release is initiated after the called subscriber has replied. When the receiver of the called subscriber is lifted metering potential is connected to the b -conductor from the final selector onwards. In the incoming repeater U_{e2} the relay $S2$ thus operates in the following circuit: potential on the b -conductor, contact $11v2$, winding II of relay $S2$, contacts $67m2$, $70u2$, earth. Relay $S2$ at contact $81s2$ interrupts the holding circuit for winding II of relay $E2$ which restores. Relay $U2$ whose energising circuit is also interrupted by opening of contact $81s2$ is maintained energised in the following circuit: earth, contacts $94u2$, $95s2$, winding III of relay $U2$, battery, earth. Relay $E2$ over its contact $62e2$ and $63e2$ momentarily connects alternating current potential WQ back over the junction VL . The connection of alternating current to the junction is terminated again when after the release of relay $E2$ relay $V2$ is energised in the following circuit: earth, contact $104v2$, winding II of relay $V2$, contact $95c2$, $98e2$, battery, earth. Relay $V2$ operates and at contact $104v2$ interrupts a short circuit for the winding I of relay $M2$ so that this relay operates in series with relay $V2$. Relay $M2$ holds in the following circuit: earth, winding II of relay $M2$, contact $82m2$, resistance $W13$, battery, earth. Now the circuit for winding II of the relay $S2$ which after the energisation of relay $V2$ was maintained over the b -conductor over contacts $12v2$, $13s2$, is interrupted at contact $67m2$. Over the closed contact $66m2$ both windings II and I are connected in series across the talking conductor in order to serve as terminating signal relays at the end of a connection. Relay $S2$ restores. Thus relay $E2$ is again energised over its winding II and by opening contact $62e2$ and $63e2$ disconnects alternating current source WQ from the junction again and on the other hand by means of contact $61e2$ and $64e2$ switches through the two talking conductors again. At the release of relay $S2$ relay $U2$ is again held over its winding II. Relay $V2$ whose circuit is interrupted at contact $98e2$ is restored and switches through the two talking conductors again at contacts $65v2$ and $11v2$.

In the outgoing repeater U_{e1} on the reply of the called subscriber short alternating current pulses are transmitted which energise the alternating current relay $J1$. Relay $J1$ over its contacts $22i1$ momentarily operates relay $H1$. Relay $H1$ closes the following circuit for relay $Y1$: earth, contacts $49x1$, $49h1$, $51e1$, winding of relay $Y1$, resistance $W11$, battery, earth. Relay $Y1$ operates and holds, after the transmission of impulses when relay $H1$ restores, in the following

circuit: earth, contact **46x1**, winding II of relay **E1**, contact **52y1**, winding of relay **Y1**, resistance **Wi1**, battery, earth. In this circuit relay **E1** also operates. By means of contact **3y1** the winding I of the impulse accepting relay **A1** is disconnected from the incoming *a*-conductor. Over contact **6e1** and the choke **Ddb** metering potential is connected to the *b*-conductor. Over contact **4e1** and choke **Dra** the transmission of the terminating signal is prepared.

Release after called subscriber's response

When at the end of the conversation the calling subscriber hangs up then in the outgoing repeater **Ue1** the seizing relay **C1** is again restored. Thus relay **A1** is energised in the following circuit: earth, contact **2i1**, winding II of relay **A1**, contact **20x1**, windings I and II of relay **H1**, contacts **25a1**, **27c1**, battery, earth. Relay **A1** closes its contact **40a1** whereby a circuit is completed over winding I of transformer **Tr** which results in the transmission of a positive inductive impulse over the junction. In series with the relay **A1** relay **H1** also energizes but only after a delay. The energising of relay **E1** over its winding I in series with the relay **H1** and relay **A1** is without effect since relay **E1** has already been energised over its winding II. Relay **V1** is energised before the relay **H1** in the following circuit: earth winding II of relay **V1**, contacts **28y1**, **27c1**, battery, earth. Relay **V1** over its contact **108v1** short-circuits relay **Y1** so that this restores slowly. Relay **Y1** on the one hand over its contact **29y1** short-circuits the winding II of relay **V1** so that this relay also restores slowly. During the release period of relay **V1** a number of inductive impulses in alternate directions are transmitted over the junction. This happens in that after the operation of relays **A1** and **H1** in series with winding II of relay **A1** the holding circuit for winding II of relay **X1** is interrupted at the contacts **50h1**, and **48a1**. Relay **X1** restores and interrupts the circuit for **A1** at contact **20x1**. The relay **A1** restores while relay **H1** is still held. Through the release of relay **A1** the circuit over winding I of transformer **Tr** is interrupted at contact **40a1** and simultaneously over contact **41a1** a further energising circuit is completed for relay **X1**: earth, contacts **41a1**, **44v1**, winding II of relay **X1**, battery, earth. Relay **X1** operates again and over contact **20x1** again connects the winding II of relay **A1** in the already described energising circuit. Relay **A1** operates further resulting in the transmission of more positive inductive impulses. As soon as relay **A1** has operated the circuit for relay **X1** is again interrupted at contacts **41a1** or **48a1** and **50h1**. Relay **X1** restores again and interrupts the circuit for winding II of relay **A1**. The release of relay **A1** results in the interruption of the circuit over winding II of transformer **Tr** and hence in the transmission of a negative inductive impulse. As soon as relay **A1** has restored an energising circuit for winding II of relay **X1** is completed. Relay **X1** operates and again closes an energising circuit for winding II of relay **A1**. This interaction is repeated until the relay **V1** has restored. The release period of relay **V1** is arranged so that about three cycles of positive and negative impulses are transmitted. The pause between the impulses, i. e., the frequency of the impulses is arranged so that in all cases a positive inductive impulse occurs in the pause between the terminating signal impulses trans-

mitted simultaneously in the opposite direction so that the release criterion is positively effective.

As soon as a positive release impulse has been received by the relay **P2** in the incoming repeater **Ue2** contact **90p2** is closed. Since however relay **M2** is energized over contact **90p2** in addition to the relay **A2** the relay **F2** is energised in the following circuit: earth, contacts **90p2**, **79m2**, winding I of relay **F2**, battery, earth. The relay **F2** immediately interrupts the circuit for relay **A2** at contact **78f2**. After the operation of relay **F2** the holding circuit for relay **C2** is interrupted at contact **99f2**. The relay **F2** holds, until relay **C2** has restored, in the following circuit: earth, winding II of relay **F2**, contacts **100f2**, **107c2**, resistance **Wi2**, battery, earth. The operation of the armature of relay **P2** by a subsequent negative impulse and the holding of contact **90p2** thus effected is in this case without effect since the relay **F2** is maintained locally over its winding II. On the operation of relay **F2** the circuit for the holding winding II of relay **E2** is interrupted at contact **106f2**. Relay **E2** restores and on the one hand interrupts the accepting circuit for the relay **P2** and on the other hand transmits guarding alternating current backwards over the junction. As soon as relay **C2** has restored as already described the release of the subsequent selectors is initiated. After the release of relay **C2** the circuit for the winding II of relay **F2** is interrupted at contact **107c2** and the relay is only maintained over contacts **97c2**, **98e2** until the subsequently arranged group selector is restored and high resistance winding I of relay **E2** has again been energised over the outgoing *c*-conductor. Thus the circuit for the winding II of relay **F2** is interrupted at contact **98e2**. On the release of relay **C2** the relay **M2** is restored by the short circuit over contacts **81s2**, **85c2**. Thus the repeater is ready to be seized again.

Release after called subscriber has hung up his receiver

If the release is performed by the calling subscriber directly on the terminating signal transmission initiated by the hanging up of the receiver of the called subscriber the following operations occur:

When the called subscriber hangs up then in the final selector of the called subscriber earth is applied to the *a*-conductor and relay **S2** of the repeater **Ue2** is energized in the following circuit: earth on the *a*-conductor in the final selector, contacts **69c2**, **65v2**, winding I of relay **S2**, contact **66m2**, winding II of relay **S2**, contact **71v2**, potential on the *b*-conductor in the final selector. Relay **S2** operates and at contact **81s2** interrupts the circuit for winding II of relay **E2**. Relay **E2** restores and thus transmits an alternating current impulse backwards over the junction **VL**. By the release of relay **E2** the following circuit is completed for relay **V2**: earth, contact **104v2**, winding II of relay **V2**, contacts **96e2**, **98c2**, battery, earth. Relay **V2** operates and at contact **65v2** interrupts the circuit for relay **S2** extending over the *a*-conductor. Relay **S2** restores and at contact **81s2** again closes the circuit for relay **E2**. Relay **E2** operates and terminates the alternating current impulse revertively transmitted. As soon as relay **E2** operates the circuit for relay **V2** is opened at contact **98e2**. Relay **V2** restores and at contact **65v2** closes the circuit for relay **S2**. Relay **S2** operates again and restores relay **E2** whereby a further alter-

nating current impulse is transmitted back over the junction. This interaction is repeated until the release impulse transmitted on the hanging up of the receiver by the calling subscriber is received by the repeater U_{e1} . The first positive inductive impulse occurring in a pause between the terminating signal impulses effects the energising the relay P_2 . Relay P_2 closes its contact $90p_2$ and thus connects the relay F_2 over contact $79m_2$. Relay F_2 holds over its winding II until the release of relay C_2 and at contact $106/2$ immediately and finally interrupts the circuit for relay E_2 , which applies guarding alternating potential back over the line. The relay P_2 is set back to its normal position over its winding II after the operation of relay F_2 in the following local circuit: earth, contacts $93u_2$, $92f_2$, winding II of relay P_2 , battery, earth. After the release of relay C_2 and operation of relay E_2 over its winding I relay F_2 finally restores. Relay M_2 is short-circuited after the release of relay C_2 over contact $85c_2$ and also restores.

The transmission of the release inductive impulse is effected in the outgoing repeater U_{e1} independently of the simultaneous terminating signals in the reverse direction, as soon as the calling subscriber has transmitted the signal for release by hanging up his receiver. Therefore as soon as the seizing relay C_1 has restored in the outgoing repeater U_{e1} the relay A_1 and relay V_1 are immediately operated and the latter at contact $39v_1$ opens a circuit maintained over contacts $38v_1$, $36e_1$ by means of relay J_1 for the receipt of the terminating signal and thus simultaneously closes the repeating circuit for the release impulse.

Release at the same time called subscriber answers

The case will now be considered in which the reply impulse of the called subscriber occurs in the return direction in the outgoing repeater simultaneously with the release initiated by the calling subscriber. In this case also the transmission of the release impulse must be ensured since the terminating signal impulse of the called subscriber can occur directly on the connection of the reply impulse. The unfavourable moment is that in which after the initiation of the release of the outgoing repeater U_{e1} relay C_1 restores and relays A_1 and E_1 are also energised. Since in this case relays Y_1 and V_1 are not yet energised the accepting circuit for the incoming reply impulse is maintained over contacts $38v_1$, $36e_1$ so that the relay J_1 is energised. Since also relay E_1 is energised the energising circuit for relay Y_1 is still interrupted at contact $42e_1$. Relay J_1 at contact $21i_1$ interrupts the circuit for relay A_1 which restores and over contact $22ii_1$ energises the relay H_1 . Relay H_1 operates. In the meanwhile over earth, contacts $46x_1$, $48a_1$, $44v_1$, $42e_1$, $45c_1$, winding II of relay B_1 , battery, earth, the relay B_1 is energised. Relay B_1 over its contact $55b_1$ short circuits relay X_1 so that this is maintained in view of the delay until the reply impulse is completed. Relay B_1 whose energising circuit was opened after the operation of relay H_1 is slow to-release due to the short-circuit of the winding I over contact $16e_1$. During the energising of relays B_1 and H_1 relay Y_1 is energised in the following circuit: earth, contacts $46x_1$, $49h_1$, $53b_1$, winding of relay Y_1 , resistance W_{11} , battery, earth. Over contact $28y_1$ the relay V_1 also operates.

At contact $44v_1$ the circuit of relay B_1 is interrupted and this relay restores slowly and at contact $54b_1$ completes the short circuit for relay Y_1 . As soon as the reply impulse is completed the relay A_1 operates again and in series therewith relay H_1 is held. Now relay X_1 restores. The interaction between relays A_1 and X_1 already described, which serves to produce the release impulse, now begins.

Figure 2 shows a variation of the principle of the invention which is obtained by slight alterations of the outgoing repeater U_{e1} shown in Figure 1. Thus in place of the number of alterations of positive and negative inductive impulses as release impulses after the reply of a called subscriber half waves of a low frequency alternating current, for example, a 25 cycle alternating current are transmitted.

For the unaltered parts of the repeater U_{e1} the same references are used as in Figure 1. The alterations in the current path are indicated by dotted lines. In detail the method of working is as follows:

When the connection according to the arrangement in Figure 1 has been set up as far as the point at which the called subscriber replies, the calling subscriber then hangs up his receiver and the seizing relay C_1 in the repeated U_{e1} restores, as already described. On the release of relay C_1 since relays X_1 , E_1 and Y_1 are energised, in the first place relays A_1 and V_1 operate immediately and then later relay H_1 . Over contact $58v_1$ the alternating current source Q of 25 cycles per second is connected to the winding I of transformer Tr . Over winding II of the transformer Tr and contact $39v_1$ the alternating current is transmitted over the junction VL to the incoming repeater U_{e2} . As soon as the first positive half wave has been received by the accepting relay P_2 the relay operates whereby as already described the release is initiated. Alternating current Q remains connected to the junction line for sufficiently long for a positive half wave to get through the terminating signal impulse occurring simultaneously in the reverse direction in all cases.

The release period of relay V_1 is dependent on the operating period of relay B_1 , the release period of relay X_1 and the release period of relay Y_1 . Moreover its own release period is extended by the short circuit of its winding. As soon as the seizing relay C_1 has restored relay B_1 operates in the following circuit: earth, contacts $46x_1$, $60y_1$, $42e_1$, $45c_1$, winding II of relay B_1 , battery, earth. Relay X_1 which after the operation of relay H_1 is held energized in the following circuit: earth, contacts $46x_1$, $69y_1$, winding II of relay X_1 , battery, earth, is short-circuited after the operation of relay B_1 over contact $55b_1$ and restores slowly. On the release of relay X_1 the circuit for relays Y_1 and B_1 is interrupted at contact $46x_1$. The circuit for the relays A_1 , H_1 and E_1 is opened at contact $26x_1$. The relays restore. After the release of relay Y_1 the relay V_1 which was short-circuited over contact $29y_1$ also restores slowly. On the release of relay V_1 on the opening of contact $58v_1$ alternating current source Q is disconnected from the junction VL .

We claim:

1. In a telephone system wherein talking connections are extended from a calling party to a called party over a trunk line which is open to direct current, means controlled by the calling party for releasing said connection either before

or after the response of the called party, means effective to transmit a single inductive impulse over said trunk line to operate said release means before said response and means effective to transmit a train of successive inductive impulses over said trunk line to operate said release means after said response.

2. In a telephone system wherein talking connections are extended from calling to called parties over a trunk line, means controlled by the response of the called party for transmitting an impulse of alternating current over said trunk line, means controlled by the calling party for producing an induced impulse of long duration and transmitting it over the trunk to release the connection before the response and means for transmitting a plurality of shorter successive inductive impulses over the trunk line thereafter to release the connection.

3. In a telephone system, a trunk line extending between exchanges and having only inductive connections with said exchanges, means for transmitting a single induced impulse over the trunk line to seize and guard the same, means for transmitting revertive impulses of alternating current in the reverse direction over the trunk line during the establishment of the connection, means for transmitting induced impulses of positive and negative polarity over the trunk line to release the connection.
4. A telephone system as claimed in claim 3 in which there is a polarized relay on the trunk line in the distant exchange which is operated by a positive induced impulse and released by a negative induced impulse.
